UNITED STATES PATENT OFFICE.

NATHAN FRIEDMAN, OF NEW YORK, N. Y.

ELECTRIC CLOCK.

No. 878,877.

Specification of Letters Patent.

Patented Feb. 11, 1908.

Application filed November 2, 1906. Serial No. 341,733.

To all whom it may concern:

Be it known that I, NATHAN FRIEDMAN, a citizen of the United States, and a resident of the city of New York, borough of Manhattan, in the county and State of New York, have invented a new and Improved Electric Clock, of which the following is a full, clear, and exact description.

My invention relates to horology, my more particular object being to produce an improved type of so-called "self-winding" time-piece, the winding being accomplished at predetermined short intervals, by the aid of an electric motor, the circuit through which is made and broken automatically by movements of the clock.

Reference is to be had to the accompanying drawings forming a part of this specification, in which similar characters of reference indicate corresponding parts in all the figures.

Figure 1 is a front elevation of a clock provided with my invention, a portion of the dial being broken away so as to show certain parts of the gearing; Fig. 2 is a fragmentary side elevation showing the general position of the electric motor, the electrical connections therefrom, the winding-shaft, and the cam mechanism connected therewith for opening and closing the circuit for energizing the motor, and thus causing the clock to be wound; Fig. 3 is an enlarged fragmentary central section showing the winding shaft, the commutator mounted thereupon, portions of the contact mechanism, the revolute armature for carrying the contact brush, and also showing the dog for stopping the clock under certain conditions, and the spring mechanism for furnishing the motive power for driving the train of gearing; Fig. 4 is a vertical section upon the line 4—4 of Fig. 3, looking in the direction of the arrow and showing the commutator and contact mechanism relating thereto; this figure also contains a diagram of the wiring and electrical connections; and Fig. 5 is a perspective of the commutator, and a portion of the winding shaft extending through it.

The casing is shown at 5, the dial at 6, hour-hand at 7 and the minute-hand at 8, these parts being of the usual or any desired construction.

A pinion 9 is disposed alongside of a gear-wheel 10, the pinion being mounted rigidly upon a revolute spindle 11, the gear-wheel

10 being loose relatively to this spindle. Meshing with the gear-wheel 10 is a pinion 12 which is rigid relatively to a gear-wheel 13. The latter meshes with the pinion 9 and causes the same to rotate; the minute-hand 8 therefore, makes the same number of revolutions as the pinion 9, while the hour-hand 7 rotates at the same rate as the gear-wheel 10. The pinion 12 and gear-wheel 13 together, rotate loosely upon a stub-shaft 13^a. The winding-shaft, which also serves as a shaft of the gearing and shown at 14, may in its entirety be seen in Fig. 3.

Located immediately back of the general gearing of the clock is an electric motor 15 provided with binding posts 16, 17 and a connecting wire 18, these posts being of the usual construction. The binding - posts 16, 17, constitute the motor terminals. By means of the wire 19, the terminal 17 is placed in electrical connection with the metallic framework 20. A corner-post 21 of the metallic frame-work just mentioned is encircled by a sleeve 22 of insulating material and mounted upon this sleeve is a brush 24 connected by a wire 23 with the motor terminal 16.

The electric motor 15 is provided with a revolute armature shaft 26 carrying at its outer end a pinion 25; the diameter of the shaft 26 being large as compared with the diameter of the pinion, in order to increase the difficulty of turning the shaft backward under tension of the winding spring. This pinion meshes with a gear-wheel 27 mounted rigidly upon the winding shaft 14. A gear-wheel 28 (see Fig. 3), is mounted loosely upon the winding shaft 14 and meshes with a lantern-wheel 29, the latter being mounted rigidly upon a revolute shaft 30; also mounted rigidly upon this shaft is a gear-wheel 31 meshing with a lantern-wheel 32, the latter together with a pallet-wheel 34 being mounted rigidly upon a revolute shaft 33. The escapement driven by the pallet wheel 34 is not shown, being of ordinary construction.

The main spring of the clock is shown at 35, and is firmly connected at 36 with the winding shaft 14 as above stated, and is revolute. The main spring is contained within a revolute barrel 37 which is provided with a pin 38 to which the outer end of the main spring is secured. The arrangement of the parts is such that according to the view shown in Fig. 4, or according to the appear- 110

ance presented to a person standing at the left of Fig. 3, the direction of movement of the winding stem 14 is "right-handed" or as it is sometimes designated, "clock-wise". A brush holder 39 having the form of an L-shaped arm is connected by lantern pins 40 with the center of the gear-wheel 28 in such manner that the lantern pins 40 being arranged in the form of a circle, virtually constitute with their connections, a lantern wheel as will be understood from Fig. 3.

A spring wire 41 is wound into a spiral form at 42, the latter being secured upon the outer end of the brush arm 39. The spring wire 41 is provided at its inner end with an enlarged rounded contact portion 43 and thus constitutes a contact brush, proper resilience to which is given by the spiral 42. A dog 44 is provided with a foot 45, and turns with the winding shaft 14, the foot 45 being normally prevented from engaging the arm 39 because of the relative movements between these two parts, as will be hereinafter explained. A disk 46 is provided with a protuberance 47 and is connected rigidly with a sleeve 48, the disk and sleeve together being secured upon the winding shaft 14 by a key 49. A similar key 50 secures the arm 44 rigidly in relation to the winding shaft 14. A sleeve 48 is provided with an eccentric portion or lobe 51, the latter being of the form indicated more particularly in Fig. 5, and provided with a spirally formed face, 51^a; that is to say the portion 51 has two faces, one a convex outer face, the other being merely a wall (51^a) the height of which diminishes at successive points around the circumference. The eccentric cam 51 is thus adapted to perform two distinct functions as a cam, and extends from the point 52 to the point 53 in Fig. 5.

A sleeve 54 of metal encircles a sleeve 55 which is mounted upon the winding shaft 14. The sleeve 54 is provided with an extension 54^a made preferably of platinum or other non-fusible or non-oxidizable material so as to present a good surface for the engagement of the enlarged portion 43 of the brush.

A sleeve 55 of insulating material is provided with portions 56, 57 of the shape indicated in Figs. 4 and 5, the sleeve thus preventing any electrical communication between the metallic sleeves 48 and 54. The battery is shown at 58 and is used for energizing the electric motor 15 as indicated.

The operation of my device is as follows: Suppose the parts are in the position indicated in Fig. 4. The metallic sleeves 48, 54, together with the insulating sleeve 55 all constitute a commutator, and are now stationary; the main spring is under tension for the reason that it has just been wound. The reaction of the spring is unable to turn the commutator backward for the reason that

the friction of the revoluble armature 26 and gearing intermediate of this armature and 65 the winding shaft 14, maintain the latter stationary for the time being. Hence, the spring in its tendency to unwind, turns the barrel 37 in a direction which, according to the view shown in Fig. 4, is "clock-wise". 70 The barrel turns the gear-wheel 28 and motion is transmitted through the several gear members 29, 30, 31, 32, and to the pallet-wheel 34 and thence to the escapement. In performing this movement, motion is con- 75 fered upon the hands 7, 8. Referring again to Fig. 4, it will be noted that the enlarged portion 43 of the brush 41 is just starting to climb upon the lobe 51; that is to say, being stationary for the time being, and the brush 80 holder 39 moving to the right or in a "clock-wise" direction, the portion 43 must move spirally outward from the point 52 to the point 53, being meanwhile pushed slightly toward the left, according to Figs. 3 and 5, 85 and guided for this purpose by the cam 46. During this time the battery circuit is open for the reason that the sleeves 48, 54, of the commutator are insulated from each other. (See Fig. 5.) Hence the motor 15 is motion- 90 less and the winding shaft 14 and the commutator (including lobe 52) are motionless. The arm 39 continues under impulse of the main-spring 35, to travel; after moving a fraction (say $\frac{1}{3}$), of a revolution the portion 95 43 of the brush reaches the point 53 upon the disk 46 and slipping the lobe 52, snaps tightly against the contact portion 54^a of the sleeve 54; that is to say, the portion 43 following the outer peripheral surface of the 100 spiral lobe 51 reaches the point 53 where the lobe tapers off to nothing, and where the portion 43 is usually supported, being in fact against the apex or protuberance 47 and having no other course except to snap in- 105 wardly against the adjacent contact portion 54^a; the following circuit is thus completed: battery 58, wire 19, portion 54^a of contact sleeve 54, wire 23, and motor 15, back to battery. This energizes the motor, and 110 causes the winding shaft 14 (carrying the commutator) to turn rapidly, thus winding the spring 35. While the spring is being wound the partial rotation of the commutator (say $\frac{1}{3}$ of a turn) causes the surface 115 51^a (see Fig. 5) to turn relatively to the brush, without allowing the latter to move sidewise. When the commutator reaches such position that the spring is completely wound, the portion 43 of the brush 41 slips off of the surface 51^a, onto the sleeve 48, at the point 52 (see Fig. 5), thus breaking elec- 120 trical communication between the part 54^a and the contact brush. The circuit being now open, the motor stops. 125

I have found that owing to the momentum acquired by the revoluble armature in mov-

ing at a high speed, the degree of rotation of the commutator is greater than would seem to be necessary, judging by the time interval during which the current is turned on. In 5 other words, the motor continues to wind the spring after the supply of electricity to the motor is cut off. This is due to the fact that the armature of the motor continues to turn, upon the principle analogous to that of a top 10 spinning, for a little time after the supply of power has ceased. The main spring of the clock therefore, acts as a brake for gradually stopping the rotation of the armature and also conserves the battery energy employed, 15 so as to render the operation more economical than would be the case if the power used in checking the rotation of the armature were merely wasted. The main spring being wound, the gear-wheel 28 continues its rotation, 20 the apparatus being now in substantially the same condition that I assumed these parts to be, in beginning to describe the operation. It will thus be seen that the commutator turns say $\frac{1}{2}$ or $\frac{1}{3}$ of a revolution 25 and stops, and that the gear-wheel 28 turns continuously, also that the commutator remains stationary until the gear-wheel 28 and arm 39 turn, say $\frac{1}{3}$ or $\frac{1}{2}$ of a revolution, and then is again turned under the action of the 30 motor so as to wind the spring.

The brush arm 39 being movable relatively to the winding shaft 14 and the dog 44 being stationary upon its shaft, it follows that the arm 39 has an angular movement in 35 relation to the dog 44; this angular movement however, is not sufficient under ordinary conditions, to bring the arm 39 into engagement with the foot 45 of the dog. The purpose of this dog is to stop the clock in case 40 the battery becomes exhausted or current otherwise becomes incapable of doing a proper amount of work. It is intended that the maximum tension of the spring shall be

constant and that the clock shall stop when this ceases to be the case.

45

It will be noted that the parts upon the winding shaft are few in number, and not liable to get out of order, and further, that they comprise a construction enabling the clock to stand rough usage. The loss of power from 50 the friction of the contact mechanism is reduced to a minimum and this enables the invention to be applied to chronometers and other delicate time-pieces.

The self-winding arrangement can be attached to any self-winding clock.

Having thus described my invention I claim as new and desire to secure by Letters Patent:

1. In an electric clock, the combination of 60 a winding shaft, a clock gear wheel loosely mounted thereon, a main spring attached to the shaft and clock gear wheel, a contact member fixedly mounted on the winding shaft, a cam fixedly mounted on the winding 65 shaft and provided with a guiding surface disposed adjacent to said contact member, a brush mounted to rotate with the clock gear wheel and electric connections for said brush and contact member.

70

2. In an electric clock, the combination of 75 an electric motor provided with a large armature shaft, a pinion mounted on said shaft, the shaft being larger in diameter than the pinion for preventing backward rotation of said shaft by power applied to the pinion, a winding shaft and gearing connecting said winding shaft to said pinion.

In testimony whereof I have signed my name to this specification in the presence of 80 two subscribing witnesses.

NATHAN FRIEDMAN.
